UNITED STATES PATENT OFFICE.

SAMUEL H. TINSMAN, OF DAVENPORT, IOWA, ASSIGNOR TO THE IMPLEMENT MANUFACTURING COMPANY, OF DAVENPORT, IOWA, A CORPORATION OF IOWA.

LISTER.

SPECIFICATION forming part of Letters Patent No. 732,140, dated June 30, 1903.

Application filed January 27, 1902. Serial No. 91,315. (No model.)

To all whom it may concern:

Be it known that I, SAMUEL H. TINSMAN, a citizen of the United States, residing at Davenport, Scott county, Iowa, have invented certain new and useful Improvements in Listers, of which the following is a specification.

My invention relates to machines for planting corn or other grain, and more particularly to machines of this character involving a plow or similar device for making a furrow and also suitable mechanism for dropping or depositing the corn or other grain in the furrow thus made. Planting-machines of this description are ordinarily known as "listers" and usually comprise, in addition to the foregoing elements, a suitable frame or body structure, a suitable number of vehicle or supporting wheels, and also suitable means for causing a relative shift between such wheels and the frame or body structure, so as to permit the plow to be raised and lowered or adjusted with respect to the character of the work.

Generally stated, the object of my invention is to provide a simple, compact, and thoroughly-efficient construction of lister.

A special object of my invention is to reduce the weight and number of parts and at the same time to insure the requisite strength and rigidity.

Furthermore, it is an object of my invention to provide an improved arrangement whereby the raising of the plow will operate to automatically disconnect the dropping mechanism from the driving means, so that the plow can be raised and the machine drawn forward without operating the dropping mechanism.

Another object of my invention is to provide a machine of this character wherein the supporting-wheels are all connected with and controlled in their movements relatively to the plow and body frame by a single hand-lever.

A further object of my invention is to provide a construction and arrangement whereby the plow-beam may be advantageously employed to serve as the frame or body structure of the machine, thereby obviating the necessity of employing cumbersome and ob-

jectionable supplemental frames or body portions.

It is also an object of my invention to provide an improved arrangement whereby a crank-axle and a bell-crank may be advantageously combined and arranged to coöperate in moving or shifting the supporting-wheels relatively to the plow and plow-beam for the purpose of either raising or lowering the plow.

In addition to these it is a special object of my invention to provide an improved arrangement of power-transmitting connection between a wheel on a crank-axle and the dropping mechanism.

My invention also involves an improved arrangement whereby a spring may be connected with all of the supporting-wheels, and thereby advantageously employed for assisting in lifting the plow from the ground.

The nature and operation of my invention, together with other advantages, will, however, hereinafter more fully appear; and to the foregoing and other useful ends my invention consists in matters hereinafter set forth and claimed.

In the accompanying drawings, Figure 1 shows one side of a lister or planting-machine involving the principles of my invention. In this view the plow is shown in a lowered or working position. Fig. 2 is a view similar to Fig. 1, but showing the opposite side of the machine. Fig. 3 is a plan of the machine shown in Figs. 1 and 2. Fig. 4 is a view of the same side of the machine as shown in Fig. 1; but in this view the plow is shown raised from the ground. Fig. 5 is a sectional detail view showing the discharge-spout for the seed or grain and also showing the swivel or pivotal connection between the rear trailing or caster wheel and the plow-beam. Fig. 6 is a detail sectional view of the bearing-bracket, which is mounted upon the crank-shaft and which supports a portion of the power-transmitting connection between one of the supporting-wheels and the dropping mechanism. Fig. 7 is a bottom view of the bracket-bearing and adjacent parts shown in Fig. 6. Fig. 8 is a detail sectional view illustrating a portion of the power-transmitting connection be-

between the rotary dropping mechanism and the driving-wheel and showing the cam device for automatically disconnecting the dropping mechanism from the driving-wheel when the 5 plow is raised from the ground. Fig. 9 is a bottom view of the devices and parts shown in Fig. 8. Fig. 10 is an enlarged detail view showing a portion of the driving-wheel and a portion of the sleeve connection between this 10 driving-wheel and the sprocket-wheel which forms a part of the power-transmitting connection between said driving-wheel and the dropping mechanism.

As thus illustrated my improved lister or 15 planting-machine comprises a plow A, which, it will be observed, is preferably provided with a double moldboard, so as to throw the dirt to each side. The machine also comprises, preferably, a plow-beam B of any suitable 20 form or construction and having its rear end secured in any suitable manner to said plow. As a matter of special improvement this plow-beam is preferably adapted and arranged to serve as the sole or only frame or body structure with which the machine is provided. 25 This obviates the necessity of providing any supplemental framework or body structure, and in this way the weight of the machine is reduced to a minimum, and, furthermore, 30 strength and rigidity are secured with a comparatively small number of parts. To such end the forward supporting-wheels C C' are preferably mounted on the spindles or end portions of the crank-axle D, which extends 35 transversely below the plow-beam at a point preferably substantially above the plow-point. The middle portion of this crank-axle is preferably mounted to turn in a bearing D', which is preferably in the form of a casting 40 properly fitted and bolted to the plow-beam. Preferably there are only three wheels in number, the third wheel being in the nature of a rear trailing or caster wheel E. This 45 caster-wheel is preferably somewhat smaller than the forward supporting-wheels and is provided with a stem e, which is arranged to turn in a box or bearing e'. In this way said 50 caster-wheel is free to swing or shift from side to side relatively to the balance of the machine and to trail behind the machine in 55 the manner of an ordinary caster-wheel. In order that this rear trailing or caster wheel may, like the forward supporting-wheels, be shifted or adjusted relatively to the plow and beam, so as to coöperate with the forward 60 supporting-wheels in raising the plow from the ground, the said box or bearing e' is preferably connected with the rear downwardly-bent portion of the plow-beam by means of 65 links or swinging arms e² and e³, arranged preferably, as shown, in upper and lower pairs, the members of each pair being arranged at opposite sides of the plow-beam and box or bearing e'. These links or swing- 70 ing arms permit a relative vertical movement between the plow and the wheel E and serve as a swinging connection whereby the plow

and beam may be raised and lowered at will. Preferably the construction and arrangement are such that all three supporting-wheels are 75 connected with and controlled by a single hand-lever F. This lever is preferably pivoted to the plow-beam at f, is provided with a dog or locking device f', adapted to engage a rack f², and is also preferably connected by 80 a link f³ with a crank-arm d, rigidly secured to the crank-axle D. One of the links or swinging arms e² is preferably provided at its lower end with a downwardly-extending lever-arm e⁴, which gives said link or swinging arm the character of a bell-crank. The lower end of this downwardly-extending arm e⁴ is 85 preferably connected, by means of a link or connecting-rod e⁵, with the crank-arm d' on the said crank-axle. This link or connecting-rod preferably has its rear end provided with a reduced portion e⁶, which is threaded to engage a threaded socket in the end of the turnbuckle or adjusting member e⁷. With 90 this provision the said turnbuckle or adjusting member e⁷ can be detached from the bell-crank lever and can then be rotated, so as to, in effect, either lengthen or shorten the link or connecting-rod e⁵. With the said hand-lever thus connected with the forward crank-shaft and with the latter connected with the rear supporting-wheel the raising and lowering of the plow or, in other words, the relative adjustment between the plow and the supporting-wheels is accomplished through 95 the medium of a single hand-lever. When the lever is thrown forward, as shown in Fig. 1, the plow is lowered to a working position and the machine is in an operative condition. When the lever is drawn back, however, as 100 shown in Fig. 4, the plow is then raised from the ground, the effect of pulling back the lever being to throw the supporting-wheels downward relatively to the plow—that is to say, to practically throw the wheels downward relatively to the plow, it being observed 105 that, strictly speaking, the effect of rotating the crank-shaft and of rocking the bell-crank about its fulcrum or pivotal point e⁸ is to either lift or depress the plow and beam, according to the direction in which the hand-lever is moved. The wheels are all connected with and simultaneously controlled or adjusted by means of a single hand-lever; but the movement is only relative, the 110 wheels, of course, remaining on the ground while the plow and beam rise or fall, according to whether the machine is to be rendered inoperative or operative. With this simple and novel arrangement and connection of the supporting-wheels the raising or lifting of the plow can be facilitated by connecting the crank-shaft with the forward portion of the plow-beam by means of a 115 spring G. The spring thus applied and arranged assists the operator in lifting the plow from the ground. At this juncture it 120 will be observed that the said operator occupies a seat H, secured at the upper end of

an upright h , which preferably rises from the box or bearing e' . In this way the weight of the driver or operator is supported more or less by the rear caster - wheel, and the weight of such driver or operator is not lifted when the lever is pulled back to raise the plow from the ground. The plow thus supported and operated is adapted to make a suitable furrow, and the dropping mechanism and other devices by which the corn, grain, or seed is deposited in this furrow may be of any suitable form or character. As a matter of further and special improvement, however, this dropping mechanism is preferably so connected with a movable member of the machine that the raising of the plow from the ground serves to automatically disconnect the rotary dropper, and thereby discontinue the discharge of the corn or seed. To such end the grain or seed can be carried in a suitable hopper I , which is preferably supported by the plow-beam at a point immediately in front of the driver's seat H . It will be readily understood that the mechanism at the bottom of this hopper for releasing the grain or seed or, in other words, dropping the same into the furrow can be of any suitable known or approved form. Preferably a spout I' leads downwardly from the bottom of this hopper to a point immediately in the rear of the plow A . As stated, the grain or seed is carried by the said hopper and is released or dropped into the discharge-spout by the dropping mechanism. For example, this dropping mechanism can be of the well-known rotary type, and the lower or rotary member i can be provided with a bevel-gear adapted to engage a relatively smaller bevel-pinion i' on the intermediate or counter shaft i^2 . This shaft, it will be observed, is arranged immediately below the hopper and dropping mechanism and is preferably supported in bearings formed by the brackets i^3 , which support said hopper. Preferably this shaft is capable of longitudinal or end movement with respect to the aforesaid automatic disconnection of the dropping mechanism when the plow is raised from the ground. The end of said shaft i^2 can be provided with a sprocket-wheel i^4 and connected, by means of a sprocket-chain i^5 , with a second intermediate or counter shaft i^6 . This intermediate shaft i^6 is preferably supported in the bracket-bearing i^7 , secured, preferably, to the crank-shaft D . Suitable sprockets and a sprocket-chain i^8 serve as power-transmitting connection between this shaft i^6 and the driving-wheel C . This driving-wheel C can be connected in any suitable way—as, for example, by a sleeve c —with the sprocket, which is connected by the chain i^8 with a sprocket on the shaft i^6 . A spring i^9 is preferably arranged to hold the bevel-pinion i' in engagement with the bevel-gear i . Thus when the plow is in the ground the driving-wheel C is connected to transmit power and motion to the rotary member i , which, as stated, may be a part of any

suitable form or construction of dropping mechanism. With the plow on the ground, as shown in Figs. 1 and 2, a forward movement of the machine causes the plow to form a furrow in the ground and also causes the driving-wheel C to operate the dropping mechanism, the seed being intermittently dropped or discharged through the discharge-tube I' and deposited in the furrow behind the plow. A link J is preferably arranged to connect the link or connecting-rod e^5 with the shaft i^2 , this link J having a slot j , in which the end of the said shaft travels. This link J is preferably provided at its upper end with a cam or bevel portion j' , adapted to engage a correspondingly-beveled collar or link j^2 on the shaft i^2 . With this arrangement the bevel-gear i , as stated, is in engagement with the bevel-pinion i' when the plow is in the ground and the machine in operative position. When the plow and beam are raised, however, as shown in Fig. 4, the cam or bevel portion j' of the link strikes the bevel ring or collar j^2 , and this causes the shaft i^2 to shift longitudinally or endwise in a direction to move the bevel-gear i' out of engagement with the bevel-pinion i . This, it will be seen, serves to break or open the power-transmitting connection between the driving-wheel and the dropping mechanism and to thereby discontinue the transmission of power from said wheel to said dropping mechanism. Thus the raising and lowering of the plow and the connecting and disconnecting of the dropping mechanism are simultaneously accomplished through the medium of a single lever. In other words, the raising of the plow serves to automatically disconnect and stop the operation of the dropping mechanism, and the lowering of the plow operates to automatically throw the dropping mechanism into connection with the driving means. If desired, the said hopper I can be hinged, as at i^{10} , to the forward side of the ring i^{11} , which is supported on the aforescribed brackets i^3 . At the rear side of said hopper it may be provided at its lower edge with a locking-bolt or similar locking device i^{12} , and with this arrangement the hopper can be readily unlocked and thrown forward, so as to permit access to be had to the under side of the dropping mechanism or to any of the other parts or devices located immediately below such dropping mechanism. If desired, the crank-axle can be provided with a plurality of removable collars or sleeve-sections c' , so as to permit the distance between the two wheels to be varied. These collars or sleeve-sections c' are, it will be observed, adapted to interlock and when adjusted into place form a practically-continuous driving-sleeve between the wheel and the sprocket for driving the dropping mechanism. As stated, however, any one of these collars or sleeve-sections can be removed and the wheel then adjusted or moved farther toward the plow, so as to reduce the space be-

tween the two wheels. It is obvious that this feature of a plurality of collars or sleeve-sections can be applied to both wheels, if so desired.

5 Thus it will be seen that by my invention I provide a frameless wheeled lister, which is characterized by a high lift and which, although of a minimum weight and number of parts, is nevertheless strong and rigid and 10 capable of efficient service in planting grain or seed. Furthermore, it will be seen that although of this character and description said lister has all the necessary and desired 15 adjustments and is readily and easily controlled with respect to the character of the work. The arrangement permits the bodily raising and lowering of the plow resulting from the relative movement between all three supporting-wheels and the plow-beam to be 20 accomplished by manipulating a single hand-lever. Thus the operation of the lister is simplified and also the weight of the machine and the number of parts are reduced substantially to a minimum. As a further 25 advantage the same lever which is employed for controlling the supporting-wheels is connected with the power-transmitting connection between the dropping mechanism and the driving means in such manner that the 30 dropping or discharge of the grain or seed is automatically discontinued when said lever is manipulated for the purpose of raising the plow. It will also be seen that the dropping mechanism and the hopper are advantageously located in front of the operator. In 35 addition to this it will be seen that the crank-axle serves as a foot-rest for the operator or driver. As another advantage the plow is practically between the two wheels, and with 40 this arrangement the plow does not tend to shift laterally and there is no lateral movement of the rear portion of the machine. As a further advantage the plow-beam is held at two points, thereby preventing the tilting or 45 up-and-down movement which characterizes the ordinary lister having the beam held at but one point. With the relative arrangement of the operating-lever and the axle-arm d' the plow-point is always below the heel, 50 regardless of whether the plow is working at the surface of the ground or at a considerable depth. When the plow is lowered to the ground, it stands substantially level, and when lowered into the ground its point or 55 toe dips relative to the heel, and the position of the point or toe relative to the heel is maintained at all points in the adjustment of the plow below the surface of the ground. For example, in Figs. 1 and 2 the plow is 60 shown lowered into the ground to a certain extent and the lever F is at a point which permits no further relative movement between the plow and the caster-wheel E. In other words, a forward movement of the lever F 65 from the position shown in Figs. 1 and 2 will produce further relative movement between the plow and the forward supporting-wheel,

but not between the plow and the rear supporting-wheel. When the lever is thrown forward from the position shown in Figs. 1 and 2, the connection between the crank-axle and bell-crank e' is simply moved vertically and not rearwardly, and hence this extreme forward adjustment of the operating-lever does not, as stated, cause any further relative movement between the plow and the rear supporting-wheel. It will be seen, however, that this extreme forward adjustment of the operating-lever causes the crank-shaft to rotate in its bearing, and consequently produce the desired further relative movement between the front supporting-wheels and the plow and plow-beam. In this way all three wheels are controlled and caused to shift relative to the plow up to a certain point in the forward adjustment of the operating-lever, and beyond such point the adjustment of the rear wheel ceases and the relative movement is confined to the forward supporting-wheels. Thus the plow is arranged for adjustment to any depth, and, as stated, the plow-point is always below the heel regardless of whether the plow is working at the surface of the ground or at some depth. With the provision of a turnbuckle e' the plow can be given any desired tilt or inclination, and this tilt or inclination is maintained at all points below the surface of the ground. Furthermore, the arrangement obviates the necessity of providing any means for locking the caster-wheel and also the necessity of providing a pole or tongue. It will also be observed that by placing the plow substantially between the two forward supporting-wheels it is possible to make a much shorter turn and to swing the machine around upon one wheel as a pivotal point.

What I claim as my invention is—

1. In a planting-machine, the combination of a device for making a furrow, front and rear supporting-wheels, a suitable hopper, a suitable dropping mechanism for controlling the discharge from said hopper, power-transmitting connection between said dropping mechanism and one of said supporting-wheels, and a lever connected and arranged for simultaneously controlling all of said wheels, so as to either raise or lower the said furrow-making device.

2. In a planting-machine, the combination of a furrow-making device, two forward supporting-wheels, a rear caster-wheel, a suitable hopper, a discharge-spout and suitable dropping mechanism for controlling the discharge from said hopper through said discharge-spout, power-transmitting connection between said dropping mechanism and one of said forward supporting-wheels, and a lever suitably connected and arranged for controlling all of said wheels, whereby said lever may be employed for either raising or lowering the said furrow-making device.

3. In a planting-machine, the combination of a suitable furrow-making device, front and

rear supporting-wheels, a suitable hopper, suitable dropping mechanism, power-transmitting connection between said dropping mechanism and one of said supporting-wheels, 5 and a lever suitably connected and arranged for both controlling said wheels and automatically disconnecting said dropping mechanism.

4. In a planting-machine, the combination 10 of a suitable furrow-making device, a pair of front supporting-wheels and a rear caster-wheel, a suitable hopper, suitable dropping mechanism, power-transmitting connection between said dropping mechanism and one 15 of said supporting-wheels, a swinging link, a cam connection between said swinging link and said dropping mechanism, and a lever connected and arranged for both adjusting said wheels and disconnecting said dropping 20 mechanism.

5. In a planting-machine, the combination 25 of a furrow-making device, two forward supporting-wheels, a rear caster-wheel, vertically swinging connections between said wheels and said furrow-making device, a suitable hopper and dropping mechanism, power-transmitting connection between said dropping mechanism and one of said forward supporting-wheels, a swinging lever, suitable connections 30 between said lever and said dropping mechanism and also between the lever and said wheels, whereby both the dropping mechanism and the raising and lowering of the furrow-making device are controlled by said 35 lever.

6. A lister comprising a plow and plow-beam, two forward supporting-wheels, a rear supporting-wheel, a hopper and dropping mechanism, power-transmitting connection 40 between said dropping mechanism and one of said wheels, and a lever for simultaneously adjusting all of said wheels relatively to the plow-beam, so as to raise and lower the plow.

7. In a planting-machine, the combination 45 of a plow and plow-beam, a plurality of supporting-wheels having shifting connections with said plow-beam, a suitable hopper, dropping mechanism having power-transmitting connection with one of said supporting-wheels, a pivoted lever, suitable connections 50 between said lever and said supporting-wheels, and suitable connections including a crank-axle and a plurality of links between said lever and said dropping mechanism, the said lever being thereby operative to control both the dropping mechanism and all of said wheels, so as to raise and lower the plow and thereby automatically disconnect the dropping mechanism.

8. In a planting-machine, the combination 60 of a suitable plow and plow-beam, a transversely-extending crank-axle, supporting-wheels on said crank-axle, a rear caster-wheel, upper and lower links connecting said caster-wheel with said plow-beam, a pivoted lever, suitable connections between said lever and said crank-axle, suitable connections between

said lever and one of said links, a hopper, dropping mechanism having suitable power-transmitting connection with one of said supporting-wheels, and suitable connections between said lever and said dropping mechanism, whereby said lever is operative to both raise and lower the plow and automatically disconnect and connect the dropping mechanism. 70 75

9. In a planting-machine, the combination 80 of a plow and plow-beam, a crank-axle provided with two supporting-wheels, a rear caster-wheel, links connecting said caster-wheel with said plow-beam, a hopper and suitable dropping mechanism, power-transmitting connection between said dropping mechanism and one of said supporting-wheels, a pivoted lever, suitable connections between said lever and said crank-axle, and suitable connections 85 between said lever and said caster-wheel, the lever thereby being operative to simultaneously control all of said wheels, to either raise or lower said plow. 90

10. In a planting-machine, the combination 95 of a suitable plow and plow-beam, a crank-axle provided with two supporting-wheels, said crank-axle extending transversely at a point substantially above the plow-point, a rear caster-wheel, shifting connection between said rear caster-wheel and the plow-beam, a suitable hopper and dropping mechanism, power-transmitting connection between said dropping mechanism and one of said supporting-wheels, a pivoted lever, suitable connections 100 between said lever and said crank-axle, and suitable connections between said lever and said caster-wheel, said lever thereby being operative to simultaneously control all of said wheels, so as to bodily raise or lower the plow and plow-beam. 105

11. In a planting-machine, the combination 110 of a plow and plow-beam, a crank-axle mounted to turn in a bearing on said plow-beam, supporting-wheels mounted to turn on each end of said crank-axle, a rear caster-wheel having a shifting connection with said plow-beam, a suitable hopper and dropping mechanism, power-transmitting connection 115 between said dropping mechanism and one of said supporting-wheels, a lever pivoted to said plow-beam, a link connection between said lever and said crank-axle, and suitable connection between said caster-wheel and the said crank-axle, said lever thereby being 120 operative to simultaneously control all of said wheels, so as to bodily raise or lower the plow and plow-beam. 125

12. In a planting-machine, the combination 130 of a suitable plow and plow-beam, forward supporting-wheels having a shifting connection with said plow-beam, a caster-wheel having a link connection with said plow-beam, one of said links being in the nature of a bell-crank, a suitable hopper and dropping mechanism, suitable power-transmitting connection between said dropping mechanism and one of said forward supporting-wheels, suit-

able connections between said lever and said forward supporting-wheels, and suitable connection between said lever and said caster-wheel, said lever thereby being operative to 5 simultaneously control all of said wheels, so as to bodily raise or lower the plow and plow-beam.

13. In a planting-machine, the combination of a suitable plow and plow-beam, a rear 10 caster-wheel having link connection with said plow-beam, a driver's seat carried by said caster-wheel, a suitable hopper and dropping mechanism mounted on said plow-beam in front of said driver's seat, forward supporting-wheels having shifting connection with 15 said plow-beam, power-transmitting connection between said dropping mechanism and one of said forward supporting-wheels, and a lever connected and arranged for causing a 20 bodily raising or lowering of said plow.

14. In a planting-machine, the combination of a suitable plow and plow-beam, supporting-wheels having shifting connections with 25 said plow-beam, a spring connected and arranged for exerting a spring tension on all 30 of said wheels, so as to tend to lift said plow, a suitable hopper and dropping mechanism, power-transmitting connection between said dropping mechanism and one of said supporting-wheels, and a lever connected and 35 arranged for simultaneously controlling all of said wheels.

15. In a planting-machine, the combination of a suitable plow and plow-beam, a forward 35 crank-axle provided with supporting-wheels, a spring connecting said crank-axle with said plow-beam, a pivoted lever, suitable connections between said lever and said crank-axle, a rear 40 caster-wheel, suitable connections between said 45 caster-wheel and said lever, a suitable hopper and dropping mechanism, and power-transmitting connections between said dropping mechanism and one of the supporting-wheels on said crank-axle, the said spring and lever coöperating to raise the plow.

16. In a planting-machine, the combination of a suitable plow and plow-beam, a crank-axle provided with supporting-wheels, a rear 50 caster-wheel, links connecting said caster-wheel with said plow-beam, a lever pivoted to said plow-beam, a link connection between said lever and said crank-axle, a link connection between said crank-axle and the caster-wheel, a suitable hopper and dropping mechanism, power-transmitting connection between 55 said dropping mechanism and one of said supporting-wheels, and a shifting member arranged to connect said dropping mechanism with the link which connects the crank-axle with the caster-wheel, said shifting member serving to automatically disconnect the 60 dropping mechanism when the lever is manipulated for the purpose of raising said plow.

17. In a planting-machine, the combination 65 of a furrow-making device, a plurality of supporting-wheels, shifting connections between said supporting-wheels and said furrow-mak-

ing device, a lever connected and arranged for controlling all of said wheels, a suitable hopper and dropping mechanism, power-transmitting connection between said dropping mechanism and one of said supporting-wheels, and a cam device intermediate of said dropping mechanism and said lever, whereby 70 said lever is operative to both raise and lower said plow and automatically disconnect and connect said dropping mechanism. 75

18. In a planting-machine, the combination of a suitable furrow-making device, forward supporting-wheels having shifting connection 80 with said furrow-making device, a rear caster-wheel, a bell-crank serving as medium of connection between said caster-wheel and said furrow-making device, a pivoted lever having suitable connection with said forward 85 supporting-wheels, a link serving as medium of connection between said bell-crank and said lever, a suitable hopper and dropping mechanism, and suitable power-transmitting connection between said dropping mechanism 90 and one of said forward supporting-wheels.

19. In a planting-machine, the combination of a plow and plow-beam, a rear caster-wheel, a bearing for the spindle of said caster-wheel, upper and lower links arranged at opposite 95 sides and serving as medium of connection between said bearing and said beam, one of said links being in the nature of a bell-crank, forward supporting-wheels having shifting connection with said plow-beam, a pivoted 100 lever having suitable connection with said forward supporting-wheels, a link serving as medium of connection between said bell-crank and said lever, a suitable hopper and dropping mechanism, and power-transmitting 105 connection between said dropping mechanism and one of said forward supporting-wheels.

20. In a planting-machine, the combination of a plow and plow-beam, forward supporting-wheels having shifting connection with said 110 plow-beam, a rear caster-wheel having a link connection with said plow-beam, one of the links being in the nature of a bell-crank, a pivoted lever having suitable connection with 115 said forward supporting-wheels, a link adjustably connected with said bell-crank and serving as medium of connection between the latter and said lever, a suitable hopper and dropping mechanism, and a power-transmitting 120 connection between said dropping mechanism and one of said forward supporting-wheels.

21. In a planting-machine, the combination of a furrow-making device, suitable supporting-wheels, a suitable hopper and dropping mechanism, a shaft below said dropping mechanism serving as medium of power-transmitting connection between said dropping mechanism and one of said supporting-wheels, said 125 shaft being mounted for end movement, a lever connected and arranged for controlling 130 said wheels, a movable member provided with a bevel or cam portion, and a collar on said

shaft arranged to be engaged by said cam portion, said lever thereby being operative to both control said wheels and automatically disconnect the dropping mechanism.

5 22. In a planting-machine, the combination of a furrow-making device, supporting-wheels, a suitable hopper and dropping mechanism, power-transmitting connection between said dropping mechanism and one of said supporting-wheels, an endwise-shiftable shaft arranged below said dropping mechanism, a suitable lever, and a cam device intermediate of said lever and said shaft, said lever thereby being operative to shift said shaft 10 and thereby automatically disconnect the dropping mechanism from the driving means.

23. In a planting-machine, the combination of a suitable furrow-making device, supporting-wheels, a suitable hopper and dropping mechanism, supporting-brackets to which said hopper is hinged, a locking device for locking the hopper in an upright position, power-transmitting connection between said dropping mechanism and one of said supporting-wheels, and a driver's seat arranged in the rear of said hopper and dropping mechanism, said hopper when thrown forward carrying the dropping mechanism out of engagement with the power-transmitting connection.

30 24. In a planting-machine, the combination of a suitable plow and plow-beam, a crank-axle mounted to turn in a bearing on said plow-beam, a lever pivoted to said plow-beam, a crank-arm on said axle, a link between said 35 crank-arm and said lever, a rear caster-wheel, links connecting said caster-wheel to said plow and beam, one of said links being in the nature of a bell-crank, a link connection between said bell-crank and said crank-axle, a 40 suitable hopper and dropping mechanism, a discharge-spout leading from said dropping mechanism to a point in the rear of said plow, supporting-wheels mounted to turn on said crank-axle, power-transmitting connection 45 between the dropping mechanism and one of the supporting-wheels on said axle, and a spring connected and arranged to assist said lever in raising the plow.

25 25. A frameless wheeled high-lift lister, comprising a suitable plow and plow-beam, supporting-wheels having a shifting connection with said plow-beam, a suitable hopper and dropping mechanism, power-transmitting connection between said dropping mechanism and one of said supporting-wheels, and a single lever connected and arranged for simultaneously controlling all of said wheels, so as to bodily raise and lower said plow and plow-beam.

60 26. In a planting-machine, the combination of a suitable plow and plow-beam, a crank-axle journaled in a bearing on said plow-beam, supporting-wheels mounted on said crank-axle, a suitable hopper and dropping mechanism, power-transmitting connection including a sleeve between one of said wheels and said dropping mechanism, said sleeve be-

ing made in sections, and the different sections being removable for the purpose of varying the distance between the two wheels, a 70 rear caster-wheel, and a lever connected and arranged for simultaneously controlling all of said wheels.

27. In a planting-machine, the combination of a suitable plow and plow-beam, a crank-75 axle, a rear supporting-wheel, forward supporting-wheels mounted on said crank-axle, a suitable hopper and dropping mechanism, power-transmitting connection including a sleeve between one of said forward supporting-wheels and the said dropping mechanism, said sleeve being composed of interlocking sections, and the different sections being removable for the purpose of varying the length of said sleeve, so as to vary the distance between 80 the two forward supporting-wheels.

28. In a planting-machine, the combination of a suitable plow and plow-beam, a suitable hopper and dropping mechanism, forward 85 supporting-wheels, a rear caster-wheel, a crank-axle upon which said plow and supporting-wheels are mounted, a pivoted lever having suitable connection with said crank-axle, a bell-crank serving as a medium of connection between said plow-beam and said 90 rear caster-wheel, a link connecting said bell-crank to one of the crank-arms of said crank-axle, a link connecting said lever with an arm on said axle, the relative arrangement of the crank-axle and lever being such that 95 the plow-point is always below the heel when the plow is in the ground.

29. In a planting-machine, the combination of a suitable plow and plow-beam, a suitable 100 hopper and dropping mechanism, forward 105 supporting-wheels, a rear caster-wheel, a pivoted lever having suitable connection with said wheels, the lever thereby being operative to simultaneously control all of the 110 wheels, so as to raise and lower the plow, the relative arrangement and the connections being such that the extreme forward throw of the lever lowers the plow without producing relative movement between the latter and the said 115 caster-wheel.

30. In a planting-machine, the combination of a suitable plow and plow-beam, a suitable 120 hopper and dropping mechanism, a crank-axle and supporting-wheels mounted on said crank-axle, a rear caster-wheel having a shifting connection with the plow-beam, a pivoted lever suitably connected with said crank-axle, a link connected between said crank-axle and said rear wheel, the lever thereby being operative to simultaneously control all 125 of the wheels, so as to raise or lower the plow, and the connections being such that the throw of the lever beyond a certain point lowers the plow without producing relative movement between the latter and the said 130 caster-wheel.

31. In a planting-machine, the combination of a suitable plow and plow-beam, a suitable hopper and dropping mechanism, forward

supporting-wheels having shifting connection with said plow-beam, a rear caster-wheel having shifting connection with said plow-beam, a power-transmitting connection between said dropping mechanism and one of said forward wheels, a pivoted lever operatively connected to simultaneously control all of the said wheels, so as to raise and lower the plow, the connections and the relative arrangement being such that the throw of

said lever beyond a certain point limits the relative movement to the forward supporting-wheels.

Signed by me at Davenport, Scott county, Iowa, this 17th day of January, 1902.

SAMUEL H. TINSMAN.
